(57) **CLAIM**

The ornamental design for an arm for a tile saw, as shown and described.

DESCRIPTION

This application is related by subject matter to application Ser. No. 29/138,021 entitled "Table for a Tile Saw," and application Ser. No. 29/138,023 entitled "Tub for a Tile Saw."

FIG. 1 is an isometric view of the arm for a tile saw; FIG. 2 is a top view of the arm for a tile saw of FIG. 1; FIG. 3 is a bottom view of the arm for a tile saw of FIG. 1; FIG. 4 is a right-side view of the arm for a tile saw of FIG. 1; FIG. 5 is a front-side view of the arm for a tile saw of FIG. 1; and, FIG. 6 is another isometric view of the arm for a tile saw of FIG. 1 shown in its environment.

The left side of the arm is not shown and forms no part of the claimed design. Each end of the arm includes mating structure, shown in broken lines in the figures, for mating the arm with other components, and the mating structure is shown for illustrative purposes only and forms no part of the claimed design. The broken line illustration of environmental structure in FIG. 6 is for illustrative purposes only and forms no part of the claimed design.
